BY Victor J. Evans

ATTORNEY

UNITED STATES PATENT OFFICE

CARL AMEL LIND, OF ALTONA, ILLINOIS

RAIL SPLICE

Application filed May 9, 1930. Serial No. 451,121.

My present invention has reference to a rail joint construction, and my primary object is the provision of a joint which will provide a substantially continuous tread surface throughout the length of the joint.

A further object is the provision of a rail joint in which the ends of the rails are cut angularly and said angle faces designed for contacting engagement and both of the said faces are channeled longitudinally to afford a pocket for a plate that comprises an electric bond so that the bond not only electrically connects the rails but being pocketed therein will hold the rail ends from vertical movement in either direction.

A further object is the provision of a rail joint which may be easily assembled and wherein the rail ends are secured to each other and secured upon the supporting ties in such manner as to entirely overcome the liability of the sinking, vertical and tilting movement of the rails at the joint thereof.

To the attainment of the foregoing and many other objects which will present themselves the invention also consists in certain other novel features of construction, combination and operative association of parts, one satisfactory embodiment of which is disclosed by the accompanying drawings.

In the drawings:

Figure 1 is a top plan view of two rails connected in accordance with this invention.

Figure 2 is a transverse sectional view on the line 2—2 of Figure 1.

Figure 3 is a similar sectional view approximately on the line 3—3 of Figure 4.

Figure 4 is a horizontal sectional view approximately on the line 4—4 of Figure 3.

Figure 5 is a perspective view looking toward the inner face of one of the rail ends.

Figure 6 is a similar view of the bond plate.

Figure 7 is a transverse sectional view therethrough.

Figure 8 is a plan view of one of the rail chairs.

Figure 9 is a perspective view of one of the spring washers.

Figure 10 is a plan view of one of the rails.

As disclosed by Figure 10 of the drawings the opposite faces of the rails 1, from the

ends thereof are cut angularly to provide contacting faces 2. To accomplish this the rails adjacent their said ends have their webs thickened.

The confronting faces of the rails are designed for snug contact and the said angle confronting faces are provided with longitudinal grooves 3 that afford pockets for bond plates 5. The plates 5, at suitable points are provided with oppositely bulged portions 6 to form a firm contact with the walls of the pockets 3, and while the length of the plate 5 is greater than that of the pockets 3 the width thereof equals the width of the said pockets and the thickness of the plates approximately equaling the depth of one of the pockets. The pockets are straight throughout. The plates are provided with elongated openings 7 which align with similar openings 8 in the ends of the rails, and through these openings there are passed the usual securing bolts 10 which are engaged by nuts 11. In the present instance the nuts have their inner faces contacted with the tangentially ribbed central portions 12 of arched spring washers 13, but these washers are not secured on the bolts until after angle fish plates 14 are arranged in the fishing spaces on the outer faces of the rails. Other bolts than those which pass through the confronting faces of the rails pass through the vertical flanges of the fish plates and through the thickened portions 16 of the rails. These bolts, indicated by the numeral 17, have their nuts contacting with arched spring washers 18 similar to the washers 13. The washers 13 and 18 will effectively prevent the nuts from unscrewing on the bolts, and the fish plate to which the shanks of the headed ends of the bolts pass have substantially rectangular openings to receive the enlarged and substantially rectangular ends of the shanks of the bolts so that the bolts will be prevented from turning in their openings.

The rails, of course, rest on ties 19, but the rails are directly supported upon tie plates 20. The tie plates have upstanding enlargements 21 adjacent to their ends providing the same with inner shoulders 22, and the said enlarged portions 21, in a line with the

shoulders 22 are provided with spike openings 23 and with outer spike openings 24. Spikes 25, respectively, pass through the openings and enter the ties 19. The central 5 spikes contact with the outer edge of the base flanges 26 of the fish plates 14, while the heads of the outer spikes 25 overlie and if desired are received in notches or depressions 27 on the edges of the said horizontal flanges 10 26 of the fish plates.

With my improvement it will be apparent that the rails cannot sink into the ties, that the joint is prevented from either upward or downward vertical movement; that the 15 joint is supported to prevent the tilting of the rails and that the heads of the rails afford a smooth tread surface throughout the length of the joint. It is thought that the foregoing when read in connection with the 20 accompanying drawings will fully set forth the construction and advantages of the device without further detailed description.

Having described the invention, I claim:

An electric bond for jointed railway rails 25 and which rails have their opposite sides cut angularly and arranged in contacting engagement, and the confronting faces thereof being grooved longitudinally and the said ends of the rails being provided with openings 30 for the reception of bolts, said bond comprising a substantially rectangular thin plate of electric conductivity of a length to be received in the grooves and to have its ends bent over the ends of the rails at the joint 35 thereof, said plate having elongated bolt openings to receive the securing bolts therethrough and having oppositely disposed outwardly bulged portions above and below the bolt openings therein and likewise having 40 a central outwardly bulged portion which is projected from the plate in an opposite direction from the first-named bulged portions and the outer walls afforded by the said bulged portion contacting with the walls 45 provided by the grooves and designed to be flattened or compressed thereagainst when the nuts for the securing bolts are screwed home.

In testimony whereof I affix my signature.

CARL AMEL LIND.
